ELECTRIC FENCE TESTER

Robert M. Wilson, Battle Creek, Mich., assignor
to Dare Products, Incorporated, Battle Creek,
Mich., a corporation of Michigan

Application March 5, 1952, Serial No. 18,778

Term of patent 14 years

(Cl. D26—1)

To all whom it may concern:

Be it known that I, Robert M. Wilson, a citizen of the United States, residing in the city of Battle Creek, county of Calhoun, and State of Michigan, have invented a new, original, and ornamental Design for an Electric Fence Tester, of which the following is a specification, reference being had to the accompanying drawing, forming a part hereof.

Figure 1 is a front view of an electric fence tester showing my new design.

Figures 2 and 3 are views from opposite sides of the body portion with the ground probe and part of the cable omitted for the convenience of illustration.

I claim:

The ornamental design for an electric fence tester, substantially as shown and described.

ROBERT M. WILSON.
